UNITED STATES PATENT OFFICE

THEODORE JAMES BASTIAN, OF LOS ANGELES, CALIFORNIA

DESIGN FOR AN AUTOMOBILE SIGNAL

Application filed January 11, 1930. Serial No. 34,100. Term of patent 7 years.

To all whom it may concern:

Be it known that I, THEODORE JAMES BASTIAN, a citizen of the United States, residing at Los Angeles, in the State of California and the county of Los Angeles, have invented a new, original and ornamental Design for an Automobile Signal, of which the following is a specification, reference being had to the accompanying drawing, forming part thereof.

Figure 1, is a side elevation of an automobile signal, showing my new design.

Figure 2, is a rear elevation.

Figure 3, is a front elevation.

I claim:

The ornamental design for an automobile signal, as shown.

THEODORE JAMES BASTIAN.
